UNITED STATES PATENT OFFICE.

ALBERT A. PAGE, OF EAST HAVEN, CONNECTICUT, ASSIGNOR TO SARGENT & COMPANY, OF NEW HAVEN, CONNECTICUT.

DESIGN FOR A PADLOCK-CASE AND HASP.

SPECIFICATION forming part of Design No. 34,320, dated April 2, 1901.

Application filed March 5, 1900. Serial No. 7,419. Term of patent 14 years.

To all whom it may concern:

Be it known that I, ALBERT A. PAGE, a citizen of the United States, residing in the town of East Haven, county of New Haven, and 5 State of Connecticut, have invented a new and useful Design for a Padlock-Case and Hasp, whereof the following is a specification when taken in connection with the accompanying drawings, which form a part thereof, 10 and in which—

Figure 1 is a front elevation of a padlock case and hasp embodying my design, and Fig. 2 a side elevation of the same.

The essential feature of my design consists 15 of a flat annular band whose inner and outer edges are concentric and are substantially uninterrupted, said annulus being divided by

lines, as a a', into two semicircular and approximately equal parts, one of said semicircular parts being thicker, viewed edge-wise, than the other, substantially as shown and described. 20

Having now described my invention, what I claim, and desire to secure by Letters Patent, is—

The design for a padlock-case and hasp herein shown and described. 25

In witness whereof I have hereunto set my hand this 28th day of February, 1900.

ALBERT A. PAGE.

Witnesses:

WILLIAM A. RICE,
NELLIE M. WEDMORE.
